UNITED STATES PATENT OFFICE.

GABE FELSENTHAL, OF LOUISVILLE, KENTUCKY.

BUTTON.

SPECIFICATION forming part of Letters Patent No. 338,055, dated March 16, 1886.

Application filed November 24, 1885. Serial No. 183,863. (No model.)

To all whom it may concern:

Be it known that I, GABE FELSENTHAL, of Louisville, in the county of Jefferson and State of Kentucky, have invented a new and useful Improvement in Sleeve and Collar Buttons, of which the following is a specification, reference being had to the annexed drawings, forming a part thereof, in which—

Figure 1 is a plan view showing the button in position to be inserted in the collar or cuff. Fig. 2 is a plan view showing the position of the parts when the button is in use. Fig. 3 is a transverse section taken on line $x-x$ in Fig. 1. Fig. 4 is a transverse section taken on line $y-y$ in Fig. 2. Fig. 5 is a sectional view taken on line $z-z$ in Fig. 1.

Similar letters of reference indicate corresponding parts in the different figures of the drawings.

20 The object of my invention is to provide a sleeve-button which may be readily introduced into and removed from the collar or cuff without exertion, and without straining or tearing the button-hole in which it is inserted.

25 My invention consists in a button having two pairs of spring-arms projecting from the back thereof, and two angled levers pivoted in the extremities of the arms, and having angled shoulders, which engage each other when the button is arranged for insertion in the button-hole and when it is in its place and in position to be worn.

30 To the back of the body of the button A are secured two pairs of spring-arms, $a-a$ and $a'-a'$, at the sides of a stop-bar, b . The two pairs of arms $a-a$ and $a'-a'$ are approximately parallel, and in the extremities of each pair of arms are pivoted the angled levers B and B' .

35 The shorter arms c of these levers are curved outward slightly, and the width of the arms c corresponds to the space between each pair of spring-arms $a-a'$. The arms d of the angled levers B and B' are wider and longer than the arms c , and are made of suitable form for retaining the button in the cuff or collar. The levers B and B' are preferably pivoted on a wire passing through the ends of each pair of the spring-arms a and a' . The plate of metal of which 40 the arms d of each lever B and B' is formed is bent at right angles at the joint, and to form

the part of the joint belonging to the lever a piece of joint-wire, e , is soldered in the angle of the lever, and the angled shoulders f of the levers, which are pressed into contact with each other by the spring-arms $a-a'$, serve to hold the levers in either of the two positions in which they may be placed.

55 The bar b between the pairs of spring arms $a-a'$ forms a stop, which limits the motion of the shorter arms c of the levers, so that the button, when in position for use, will always assume a symmetrical form, and the arms d will be parallel with the face of the button. The button is put into position for use by 60 bringing the arms d parallel to each other, as shown in Figs. 1 and 3. These arms are then inserted in the button-hole g , the button is pushed forward toward the cuff until the arms c of the levers B strike the surface of the cuff, 65 and by throwing these arms toward the body of the button the arms d are thrown outward away from each other within the cuff, and when the contact-line of the angled shoulders f lies outside of the pivotal center of the levers B and B' the spring-arms a and a' , by pressing the levers B and B' toward each other, will complete 70 the movement of the levers and bring them into the position shown in Fig. 4.

75 When it is desired to remove the button from the cuff, it is withdrawn by pulling the body of the button outward, bringing the arms d of the levers B and B' into engagement with the inner surface of the cuff, thus turning them on their pivots and bringing 80 them into the original position shown in Fig. 3.

85 The spring of the arms $a-a'$ is sufficient to keep the levers B and B' in either of the positions in which they are placed.

90 It will be noticed that my improved sleeve-button is entirely automatic in its operation, and when it is withdrawn from the cuff it is in position to be again inserted, so that no manipulation other than inserting it into and removing it from the button-hole is necessary.

Having thus described my invention, what I claim as new, and desire to secure by Letters Patent, is—

95 1. In a sleeve-button, the combination, with 100 the button-body, of the spring-arms $a-a'$, forming the shank of the button, and angled le-

vers B B,' pivoted to the spring-arms and provided with angled shoulders *f*, pressed into engagement with each other by the spring-arms *a a'*, substantially as herein shown and described.

2. As an improved article of manufacture, a sleeve-button formed of the body *A*, two pairs of spring-arms, *a a'*, projecting from the body, two angled levers, *B B'*, pivoted to the

spring-arms and provided with angled shoulders *f*, and the stop *b*, placed between the spring-arms *a a'*, substantially as herein specified.

GABE FELSENTHAL.
